UNITED STATES PATENT OFFICE

147,630

DESIGN FOR A BOTTLE OR ARTICLE OF
SIMILAR NATURE

John S. Allen, Montgomery, Ala.

Application March 27, 1946, Serial No. 128,004

Term of patent 14 years

(Cl. D58—8)

To all whom it may concern:

Be it known that I, John S. Allen, a citizen of the United States of America, residing at Montgomery, in the county of Montgomery, State of Alabama, have invented a new, original, and ornamental Design for a Bottle or Article of Similar Nature, of which the following is a specification, reference being had to the accompanying drawing, forming part thereof.

I claim:

The ornamental design for a bottle or article of similar nature, as shown.

JOHN S. ALLEN.
